UNITED STATES PATENT OFFICE

WILLIAM H. WILSON, OF BURLINGTON, VERMONT, ASSIGNOR TO VERMONT SPOOL & BOBBIN CO., OF BURLINGTON, VERMONT, A CORPORATION OF VERMONT

SPOOL FOR AXMINSTER LOOMS

Application filed November 24, 1928. Serial No. 321,671.

This invention relates to spools for Axminster looms and it is the general object of the invention to provide improved means to secure a bearing gudgeon to a spool so that the gudgeon will be held against undesired rotation relatively to the spool as the latter is supported either in a winding frame or in an Axminster loom.

In my prior Patent No. 1,683,224 I have shown a spool for use in Axminster looms wherein a wooden barrel has parallel grooves cut across the end thereof to receive corresponding corrugations struck from a flat steel spool head. A bolt or gudgeon formed with an enlarged bearing element passes through the steel head into the wooden barrel and is the means by which the head is secured to the spool. The corrugations very effectively prevent rotation of the steel head with respect to the barrel, but under some conditions I find that the gudgeon has a tendency to work loose and it is an important object of my present invention to provide a washer or similar device which will be held against rotation by the aforesaid corrugations and at the same time will be so related to the gudgeon as to prevent angular movement thereof.

It is a more particular object of my present invention to provide between the corrugated steel head and the enlarged bearing portion of the gudgeon a washer having lugs to extend into the corrugations of the steel head and having also a tongue which may be deflected to enter any one of a plurality of notches formed in the bearing portion of the gudgeon, said tongue when bent into position serving effectively to hold the several parts of the spool against relative angular motion.

With these and other objects in view which will appear as the description proceeds, my invention resides in the combination and arrangement of parts hereinafter set forth and described in the claims.

In the accompanying drawing wherein a convenient embodiment of my invention is set forth,

Fig. 1 is a top plan view of a spool made

according to my present invention and adaptable for use in an Axminster loom,

Fig. 2 is a view on an enlarged scale taken in the same direction as Fig. 1 showing the steel head, gudgeon securing lug for the latter and the washer, said parts being separated and partly in section to illustrate the aforesaid notches,

Fig. 3 is an enlarged plan of one end of the spool shown in Fig. 1,

Fig. 4 is a vertical section on line 4—4 of Fig. 3,

Fig. 5 is a horizontal section taken on line 5—5 of Fig. 4,

Fig. 6 is an end elevation taken in the direction of arrow 6, Fig. 4, and

Fig. 7 is a detailed perspective view of the washer.

A spool of the type to which my invention relates will ordinarily include in its construction a cylindrical barrel 10 provided with a longitudinal groove or slot 11 running the full length of the barrel to receive a yarn securing rod not shown herein. The yarn space is defined by heads 12 which in the present instance are preferably made of steel and formed with a plurality of parallel spaced corrugations 13 which as shown in Fig. 6 may extend across the central portion of the head.

These corrugations fit into corresponding grooves 14 which extend across the ends of the barrel, said grooves being spaced apart a proper distance to receive the several corrugations. The ends of the spool are preferably made alike so far as the corrugations of the steel head are concerned and may be made alike so far as other features to be described are concerned. Ears 15 are struck from the steel head and extend into engagement with the side parallel walls of the slot 11.

A gudgeon or bearing member 16 extends into each end of the barrel 10, each gudgeon having a body portion 17 to be received by a bore 18 of the barrel and having preferably a reduced portion 19 which may be threaded into a metallic block 20. The latter may lie in a lateral aperture 21 which intersects the bore 18 as shown in Fig. 5 and each block is

internally threaded to receive the threaded end 22 of the corresponding gudgeon 16.

The outer end of each gudgeon may have an enlarged bearing portion 23 from which 5 may extend a projection 24 having parallel sides to engage a complementarily formed gudgeon on an adjacent spool.

The matter thus far described may be substantially the same as set forth in my afore- 10 said patent, the bearing portion 23 being larger than the body portion 17 and serving to hold the corrugations 13 in the grooves 14.

My improvements relate particularly to the means for preventing relative rotary motion 15 between the barrel, or more properly the block 20, and the gudgeon, and in carrying my invention into effect I interpose between bearing portion 23 and the central portion of the steel head a washer of the general form 20 shown in Fig. 7 and designated at 30. Said washer may have one or more small lugs 31 proportioned to enter one or another of the corrugations 13 which extend inwardly from the outer plane face of the head 12. The 25 washer is provided with a bore 32 through which extends the body portion 16 of the gudgeon. The lug or lugs 31 act to prevent relative movement of the washer with respect to the head 12.

30 The washer is further provided with a tongue 33 which is proportioned to enter a notch 34 formed in the bearing portion 23 as shown in Figs. 2 and 4. There may be several of these notches although I have 35 shown herein only two, but I do not wish to be limited to a single tongue 33 on the washer.

In assembling the several parts of the spool the steel head will first be fitted to the end 40 of the spool with the corrugations 13 properly received by the corresponding grooves in the barrel. The washer 30 will then be placed so that its bore 32 will align with the bore 50 in the center of the steel head and the gudgeon will be passed through said washer and steel 45 head. The block 20 which may have previously been inserted in the passage or aperture 21 will receive the threaded ends of the gudgeon and the latter will be turned until the gudgeon is almost in its final position.

50 The lug or lugs 31 will then be aligned with the corresponding corrugations and the gudgeon threaded into the block until tight. The parts will be tightened until one of the notches 34 is in alignment with the tongue 55 33, after which the latter will be bent into the adjacent notch by a suitable tool. By this last operation all of the parts of the spool will be held against relative rotary motion and the gudgeon will not be able to turn 60 in the bore 18, with the result that the steel heads 12 will be held accurately in position so that the warp threads wound on the barrel 10 will occupy an accurately defined warp space.

65 From the foregoing it will be seen that I

have provided a simple device to operate in conjunction with the corrugations in the head of a spool to prevent loosening of the bearing gudgeon. While I have shown but one tongue 33 yet it is obvious that more than 70 one can be distributed around the periphery of the washer and it is likewise obvious that I am not restricted to the use of two notches 34.

Having thus described my invention it 75 will be seen that changes and modifications may be made therein by those skilled in the art without departing from the spirit and scope of the invention and I do not wish to be limited to the details herein disclosed, but 80 which I claim is:

1. In a spool having a barrel provided with grooves across the ends thereof and having a gudgeon extending from the barrel provided with a bearing surface having a portion thereon to engage a complementarily formed gudgeon on an adjacent spool, a spool head substantially perpendicular to the axis of the barrel and having corrugations on one side to enter the grooves and 90 corresponding recesses on the opposite side, said gudgeon extending through the head and secured at its inner end with respect to the barrel and having a cylindrical bearing surface, means defining a slot in the bearing 95 surface of the gudgeon, and a member lying within the periphery of the bearing surface and having a portion to extend into the slot to prevent angular movement between the member and gudgeon, and additional means on the member to hold said member against relative angular movement with respect to the spool.

2. In a spool for an Axminster tube frame having a barrel provided with grooves across the end thereof and having a gudgeon extending from the barrel provided with a bearing surface having a portion thereon to engage a complementarily formed gudgeon on an adjacent spool, a longitudinally extending groove on the periphery of the barrel, a spool head substantially perpendicular to the axis of the barrel and having corrugations on one side to enter the grooves across the barrel and having corresponding recesses on the other side, means defining a slot in the bearing surface of the gudgeon, projections on the head to fit the longitudinally extending grooves on the barrel to align the head, and a member located between the bearing surface of the gudgeon and lying within the outline of the latter and the head, said member having a portion to engage the slot in the bearing surface of the gudgeon and having another portion to enter a recess in the head to prevent relative angular motion between the gudgeon and member.

3. In a spool having a barrel provided with grooves across the end thereof and having a gudgeon fixed relatively thereto, said 130

gudgeon having a portion to engage a complementarily formed adjacent spool, a spool head substantially perpendicular to the axis of the barrel and having corrugations on 5 one side to enter the grooves and corresponding recesses on the opposite side, a bearing element formed on the gudgeon and having a recess defined by walls which are substantially parallel to the axis of the gudgeon 10 and having a cylindrical bearing surface, and a washer located between the bearing element and the spool head and having a tongue to enter the recess in the cylindrical surface of the bearing element and engage 15 the walls of said recess, said washer lying within the outline of the bearing element.

In testimony whereof I have hereunto affixed my signature.

WILLIAM H. WILSON.
